UNITED STATES PATENT OFFICE.

JOHN U. BARR, JR., OF PITTSBURG, PENNSYLVANIA, ASSIGNOR OF ONE-HALF TO DAVID J. RICHARDSON, OF ALLEGHENY, PENNSYLVANIA.

ILLUMINATED-SIGN APPARATUS.

SPECIFICATION forming part of Letters Patent No. 573,436, dated December 22, 1896.

Application filed December 19, 1895. Serial No. 572,641. (No model.)

To all whom it may concern:

Be it known that I, JOHN U. BARR, Jr., a resident of Pittsburg, in the county of Allegheny and State of Pennsylvania, have invented a new and useful Improvement in Illuminated-Sign Apparatus; and I do hereby declare the following to be a full, clear, and exact description thereof.

My invention relates to illuminated-sign apparatus.

The object of my invention is to provide an apparatus for automatically exhibiting upon the street, pavement, wall, screen, or the like a series of illuminated pictorial or other objects in succession for advertising or other purposes and to provide a novel apparatus which can be employed for indicating the exact time or hour of the day or night as well as the advertising.

To accomplish these objects, my invention involves the features of construction, the combination or arrangement of elements, and the principles of operation hereinafter described and claimed, reference being made to the accompanying drawings, in which—

Figure 1 is a side view of the box containing the apparatus embodying my invention. Fig. 2 is a vertical central section of the box. Fig. 3 is an enlarged top view of the apparatus employed. Fig. 4 is an enlarged bottom view thereof. Fig. 5 is a side view of the apparatus. Fig. 6 is an enlarged cross-section on the line 6-6, Fig. 3; and Fig. 7 is an enlarged detail view.

Like letters indicate like parts in each of the figures of the drawings.

The box A is preferably formed of metal, such as tin, &c., and is provided with the openings a for ventilating purposes. At the lower end of the box A is the neck b, around which are formed the openings c in the bottom c' of the box A to further ventilate the same. Below the neck b is the receptacle d for the reception of the apparatus B, and a neck e' is formed in the door or lid e below the receptacle d for the lens f.

As preferred by me, an incandescent electric lamp g enters the top of the box A opposite the neck b, and a reflector h is hung within the box A above the lamp g, so that the rays of light are reflected through the neck b

and apparatus B, as hereinafter described. The apparatus B is passed into the receptacle d through the door e and is held therein by pins d' on the blocks d², the said pins d' entering the notches i' in the circular plate i of the apparatus B, and upon the apparatus B being turned one of the pins d' will come in contact with the stop i², so holding the apparatus B securely within the receptacle d. The apparatus B rests against the blocks d², so forming an air-space d³ between the top of the receptacle d and the apparatus B. Secured to the bottom face i³ of the circular plate i at one side thereof is the ordinary clockwork mechanism C used for indicating the time, the hand-operating shaft j of which extends through the circular plate i and has the gear-wheels j' j² thereon above the top face i⁴ of the plate i. An opening k' is formed in the plate i, within which is secured the glass clock-dial k, containing the different time-characters thereon, and fitting around the dial k is the case l, which has the flange l' on its top edge and the flanges l² around the sides thereof for securing it to the top face i⁴ of the plate i.

Fitting loosely within the case l and held therein by the flange l' is the loose ring m, around the outside periphery of which is the gear-face m', which meshes with the gear-wheel j' on the shaft j through an opening l³ in the side of the case l. Between the loose ring m and the dial k is the glass plate n, which is loosely held within the case l by means of the ring n', secured around the same and provided with the gear-face n², which meshes with the gear-wheel j² on the shaft j. The minute-hand m² is rigidly secured to the inside face of the loose ring m, and the hour-hand n² is rigidly secured by cement or in any other suitable manner to the upper surface of the glass plate n.

Passing through the center of the plate i is the shaft o, to which is connected the clockwork mechanism D, the said clockwork mechanism being used for displaying the different advertisements and being rigidly secured to the bottom face i³ of the plate i by means of the frame D', which supports the said clockwork mechanism D and the clockwork mechanism C.

Secured to the upper end of the shaft o , between the plates o' o'' , is the glass disk p , which is formed circular and is provided with a number of advertising-spaces p' thereon, the said disk p being held between the plates o' o'' by means of the nut o^3 engaging with the end of the shaft o by screw-threads in the ordinary manner. Secured upon the shaft q of the clockwork mechanism C is the ratchet-wheel q' , within which engages the pawl q^3 , secured on the lower end of the lever q^3 , the upper end of which is rigidly secured around a rock-shaft r , passing through the frame D' of the clockwork mechanism C. A spiral spring q^4 connects the lever q^3 and the frame D' at q^3 . The shaft r is also provided with a lever s , which is connected thereto at one end, and its opposite end is provided with two projecting flanges s' s'' , having an opening s^3 between them for a pin t' on a gear-wheel t , located in the clockwork mechanism D and engaging with a small gear-wheel t^2 on a shaft r' in the clockwork mechanism D for operating the disk p to operate and change the advertisements. A small opening s^4 is formed in the flange s^2 for the entrance of the pin t' into the opening s^3 between the flanges s' s'' . The clockwork mechanism C and the clockwork mechanism D are almost identical in form, except that the clockwork mechanism D is minus the balance-wheel u , hair-spring u' , and regulator u^2 , such as is shown on the clockwork mechanism C in Fig. 4. A handle r is secured to the bottom face i^3 of the locator-plate i for the purpose of inserting and withdrawing the apparatus from the box A. The operation of my improved illuminated-sign apparatus is as follows: After the clockwork mechanism C and D of the apparatus B have been wound up in the ordinary manner and the balance-wheel u is started the apparatus B is inserted within the receptacle d of the box A, which has been so placed that the time and advertisements will be thrown upon the street, sidewalk, wall, or screen, as desired. Upon the movement of the balance-wheel u the clockwork mechanism C is put into operation, and through the medium of the chain of gearing therein the shaft j is turned to indicate the time by means of the gear-wheel j' on the shaft j meshing with the gear-face m' on the loose ring m on the loose minute-hand m^2 and the gear-wheel j^2 on the shaft j meshing with the gear-face n^2 on the ring n' , secured around the glass plate n , carrying the hour-hand n^3 . During the movement of the clockwork mechanism C the shaft q therein is slowly revolved, imparting motion to the ratchet-wheel q' , connected thereto. As the ratchet-wheel q' is turned the pawl q^3 , engaging therewith, frees itself about every three minutes and, through the lever q^3 , connected to the rock-shaft r , raises the flanges s' s'' on the lever s from engagement with the pin t' on the gear-wheel t in the clockwork mechanism D, so allowing the gear-wheel t to revolve and, through the chain of gearing in

the clockwork mechanism D, turning the shaft o therein slightly in order to place one of the advertising-spaces p' opposite the center of the glass plate n and clock-dial k . While the gear-wheel t is revolving and the chain of gearing in the clockwork mechanism D is operating the pawl q^3 is held from engagement with the ratchet-wheel q' until the disk p is moved, during which time the spiral spring q^4 , connected to the lever q^3 , is expanded. After the disk p is moved the required distance the spiral spring q^4 is compressed, so bringing the pawl q^3 into engagement with another tooth in the ratchet-wheel q' and the pin t' on the gear-wheel t into contact with the flanges s' s'' on the lever s , so as to be ready for another operation. While the apparatus B is in the receptacle d of the box A the lamp g is above and opposite one of the advertising-spaces p' on the disk p , which appears opposite the center of the glass plate n and dial k , so that the time indicated by the hands m^2 n^3 on the ring m and glass plate n , with the characters on the glass dial k , will appear on the sidewalk, street, screen, or other suitable place, as well as the advertisement in the space p' , when the light is reflected from the lamp g by means of the reflector h down through the neck b , disk p , glass plate n , dial k , and lens f in the neck e' .

It will thus be seen that by the use of my improved illuminated-sign apparatus different advertising-signs can be shown upon the sidewalks, streets, walls, or screens, as well as the exact time of the day or night. The number of advertisements can be changed at will and can be shown as rapidly as desired by the simple changing of the parts. The apparatus is automatic in its action and does not require any attention whatever except the winding of the mechanism at the proper time when it has run down. The parts are simple in their construction and durable, and the apparatus is not liable to get out of order or be affected by the weather.

Various modifications in the construction and position of the various parts of the apparatus may be resorted to without departing from the spirit of the invention or sacrificing any of its advantages.

What I claim as my invention, and desire to secure by Letters Patent, is—

1. An illuminated-sign apparatus, comprising a lens and a source of light, a clock-dial, means for indicating the time, mechanism carrying a picture or pictures, and means for operating the time-indicating apparatus and picture-carrying mechanism; substantially as described.

2. An illuminated-sign apparatus, comprising a lens and source of light, a picture or pictures, a transparent clock dial and hands, and mechanism connected to said picture or pictures and clock-hands whereby the picture or pictures and time indicated by the clock dial and hands are displayed upon a surface at the same time, substantially as described.

3. An illuminated-sign apparatus, comprising a lens and a source of light, a transparent clock-dial, means for indicating the time, mechanism carrying a picture or pictures, 5 and means for operating said time-indicating apparatus and picture-carrying mechanism; substantially as described.

4. An illuminated-sign apparatus, comprising a lens and a source of light, a clock-dial, 10 means for indicating the time, mechanism carrying a picture or pictures, and means for operating said time-indicating apparatus and picture-carrying mechanism, the entire apparatus being contained in a box or case; substantially as described.

5. An illuminated-sign apparatus, comprising a box or case containing a lens and the source of light, a set of pictures within said box or case, a transparent clock-dial between 20 the pictures and lens, a minute and hour hand carried on separate parts, and mechanism connected to said pictures and parts carrying the minute and hour hands whereby the pictures and time indicated on the clock-dial by 25 the minute and hour hands are automatically displayed upon a surface, substantially as described.

6. An illuminated-sign apparatus, comprising a lens and a source of light, a clock-dial, 30 means for indicating the time, mechanism carrying a picture or pictures, means for operating the time-indicating apparatus, and means for operating the picture-carrying mechanism operatively connected to the apparatus for working the time-indicating mechanism; substantially as described.

7. An illuminated-sign apparatus, comprising a lens and source of light, a clock-dial, means for indicating the time, mechanism 40 carrying a picture or pictures, clockwork mechanism for operating said time-indicating apparatus, and clockwork mechanism for operating said picture-carrying mechanism; substantially as described.

45 8. An illuminated-sign apparatus, comprising a lens and source of light, a clock-dial, means for indicating the time, mechanism carrying a picture or pictures, clockwork mechanism for operating said time-indicating mechanism, and clockwork mechanism for operating said picture-carrying mechanism operatively connected to said first-named clockwork mechanism; substantially as described.

55 9. In illuminated-sign apparatus, the combination with a box or case, containing a lens and the source of light, of a set of pictures within said box or case, a clock-dial, clock-hands mounted on separate parts, clockwork 60 mechanism for operating the clock-hands, clockwork mechanism connected to the pictures, and mechanism connected to said first clockwork mechanism for operating the second clockwork mechanism to automatically 65 change or shift the pictures, substantially as described.

10. In illuminated-sign apparatus, the com-

bination with a box or case containing a lens and the source of light, of a set of pictures within said box or case, a clock-dial, clock-hands mounted on separate parts, clockwork mechanism for operating the clock-hands, clockwork mechanism connected to the pictures, a ratchet-wheel on said first clockwork mechanism, a spring-lever having a pawl 70 thereon engaging with said ratchet-wheel, a shaft connected to said spring-lever, and a lever connected to said shaft at one end and having its opposite end engaging with a pin on a gear-wheel mounted on a shaft in the second clockwork mechanism to automatically 75 change or shift the pictures, substantially as described.

11. In illuminated-sign apparatus, the combination with a box or case containing a lens 85 and the source of light, of a plate or body portion secured within the box or case, a transparent clock-dial secured within said body portion, a transparent plate having the hour-hand secured thereto, a flanged case 90 around the transparent plate, a loose ring within the flanged case having the minute-hand secured thereto, clockwork mechanism secured to said body portion, and gear-faces around said transparent plate and loose ring 95 adapted to engage with gear-wheels on a shaft in the clockwork mechanism, substantially as described.

12. In illuminated-sign apparatus, the combination with a box or case containing a lens 100 and the source of light, of a plate or body portion secured within the box or case, a transparent clock-dial secured within an opening in the body portion, a transparent plate having the hour-hand secured thereto, 105 a flanged case around the transparent plate, a loose ring within the flanged case having the minute-hand secured thereto, clockwork mechanism secured to said body portion at one side thereof, gear-faces around the transparent plate and loose ring adapted to engage 110 with gear-wheels on a shaft in the clockwork mechanism, a disk carrying a set of pictures secured on a shaft located within the body portion, clockwork mechanism connected to 115 said shaft, and mechanism connected to said first clockwork mechanism for operating the second clockwork mechanism to automatically change or shift the pictures, substantially as described. 120

13. An illuminated-sign apparatus, comprising a lens and the source of light, a transparent clock-dial, a transparent plate having the hour-hand secured thereto, a loose ring having the minute-hand secured thereto, and mechanism for operating said transparent plate and loose ring; substantially as described. 125

14. An illuminated-sign apparatus, comprising a lens and a source of light, a transparent clock-dial, a transparent plate having the hour-hand secured thereto, a flanged case around the transparent plate, a loose ring within the flanged case, and mechanism for 130

operating said transparent plate and loose ring; substantially as described.

15. An illuminated-sign apparatus, comprising a lens and source of light, a transparent clock-dial, a transparent plate having the hour-hand secured thereto, a flanged case around the transparent plate, a loose ring within the flanged case, and gear-faces around said transparent plate and loose ring adapted

to engage with gear-wheels on a shaft in the 10 clockwork mechanism; substantially as described.

In testimony whereof I, the said JOHN U. BARR, Jr., have hereunto set my hand.

JOHN U. BARR, JR.
